B. M. CLEVELAND

PUMP JACK

Filed July 7, 1925

B. M. Cleveland.

Inventor

By *Clarence A. O'Brien*
Attorney

UNITED STATES PATENT OFFICE.

BURNS M. CLEVELAND, OF PRAIRIE LEA, TEXAS.

PUMP JACK.

Application filed July 7, 1925. Serial No. 41,994.

The present invention relates to a pump jack such as are used in pump rigs for wells, and has for its prime object to provide a structure for translating reciprocating motion in one direction to reciprocating motion in another direction wherein there is utilized a wheel having sprocket chains associated therewith being connected to the wheel at points in the same radius of the wheel and 10 extending about the wheel in opposite directions, and a weight mounted on the wheel to hold the same normally in a predetermined position.

Another important object of the invention 15 lies in the provision of an exceedingly simple construction, one which is clearly reliable and efficient in operation, strong and durable, inexpensive to manufacture, not likely to easily become out of order, and 20 otherwise well adapted for the purpose for which it is designed.

With the above and numerous other objects in view as will appear as the description proceeds, the invention resides in certain 25 novel features of construction, and in the combination and arrangement of parts as will be hereinafter more fully described and claimed.

In the drawing:—

30 Figure 1 is an elevation of the device embodying the features of my invention, and Figure 2 is a bottom plan view thereof. Referring to the drawing in detail it will be seen that 5 designates a hub having a disc body 6 mounted thereon provided with a plurality of concentric rings 7 arranged on the faces thereof. Adjacent each ring 7 there is provided in the disc body 6 a plurality of apertures 8 so that sprocket teeth 35 sections 9 may be attached about the ring by suitable fastening elements passing therethrough and through the apertures 8. There will be a set of these sections 9 on each side of the wheel. Spokes 10 radiate from the 40 periphery of the disc body and support a rim 11 provided with sprocket teeth 12.

A chain 13 has its end link 14 pivotally engaged with one of the spokes 10, as is indicated at 15, and is trained about the rim 45 11 in engagement with a portion of the sprocket teeth 12 as is clearly indicated in Figure 1. Chain sections 16 have their end

links fixed as at 17 to one of the end sections 9 so as to be in radial alignment with the pivot point 15. These chain sections 16 are 50 trained over the teeth sections 9, and then extend outwardly or tangentially so that the tangential portion of the sections are disposed at right angles to the tangential portion of the chain 13. A heavy weight 18 55 is fixed to two of the sprockets as is indicated at 19. There are preferably two of these weights, one on each side of the wheel, and they normally hold the wheel in the position shown in Figure 1. It will thus be 60 seen that a pull to the left on chain section 16 will rotate the wheel, thereby causing an upward pull by the chain 13. The weights 18 will return these parts to their initial position. It is thought that the construction, 65 operation, and advantages of this invention will now be clearly understood by those skilled in the art without a more detailed description thereof. It is desired, however, to point out that the leverage of the device 70 can be changed by locating the teeth sections 9 adjacent different rings 7 as will be apparent.

The present embodiment of the invention has been disclosed merely by way of example, since in actual practice it attains the various features of advantage enumerated as desirable in the statement of the invention, and the above description. It will be apparent that numerous changes in the details 80 of construction, and in the combination and arrangement of parts may be resorted to without departing from the spirit or scope 85 of the invention as hereinafter claimed or sacrificing any of its advantages.

Having thus described the invention, what I claim as new and desire to secure by Letters Patent is:—

A wheel of the class described including a 90 plurality of concentric rings arranged thereon in spaced relation, removable sprocket teeth sections associated with the rings, a chain associated with the teeth sections, and sprocket teeth arranged about the periphery 95 of the wheel and having a chain associated therewith.

In testimony whereof I affix my signature.

BURNS M. CLEVELAND.
